[57]**CLAIM**

The ornamental design for a photo mount device, substantially as shown and described.

DESCRIPTION

FIG. 1 is a perspective view of a photo mount device showing the front, top and left side of our new design, the right side being a mirror image thereof;

FIG. 2 is a rear elevational view thereof;

FIG. 3 is a left side elevational view thereof; and

FIG. 4 is a top plan view thereof.
